UNITED STATES PATENT OFFICE.

MATILDA HAMEL, OF WATERLOO, ONTARIO, CANADA.

CREAM-BOTTLE.

1,300,607.

Specification of Letters Patent. Patented Apr. 15, 1919.

Application filed November 27, 1918. Serial No. 264,380.

To all whom it may concern:

Be it known that I, MATILDA HAMEL, a citizen of Canada, residing at Waterloo, Province of Ontario, and Dominion of Canada, have invented certain new and useful improvements in Cream-Bottles, of which the following is a specification.

This invention relates to bottles and jars, and more especially to compartment bottles; 10 and the object of the same is to produce a peculiar form of container, preferably of glass having a movable partition.

Broadly speaking, the general use of my 15 invention is to permit the operator to raise the partition within the bottle or jar to a point where it separates the milk from the cream, meanwhile lifting off the closure so that he can then pour off the cream and retain the milk; but I do not wish to be limited 20 to this use of my invention, as it may be employed for separating any two substances within the container.

A feature of the invention also is the peculiar means employed for retaining the partition in its position.

Another feature is the peculiar means employed for automatically lifting off the closure when the partition is raised.

Details are set forth in the following 30 specification and claims and reference is made to the drawings, wherein—

Figure 1 is a side elevation partly broken away.

Fig. 2 is a vertical section on line 2—2 35 of Fig. 1.

Fig. 3 is a horizontal section on the line 3—3 of Fig. 2.

The container 1 I speak of herein as a bottle or jar because I prefer to make it of 40 glass. It has a body which is preferably cylindrical on the interior throughout its entire height, and around its upper end it is enlarged to produce a shoulder 2 facing downward, while internally the mouth of the 45 container is enlarged to produce a shoulder 3 on which rests the closure 4 which is herein shown as a paper cap having notches 5 in its opposite edges for purposes yet to appear. The bottom 6 of the body may be raised a 50 little, and the whole may be of any desired size.

Within the body is movably mounted a 55 partition 11 also by preference of glass, and this partition has a pair of lugs 12 on its upper side pierced with holes through which passes the lower stretch 13 of a loop 14

which may well be of aluminum or other non-corrosive wire. The side bars of this loop rise within the walls of the body and pass out its mouth, and they are connected 60 at the top by a cross bar constituting a handle 15. The length of the loop is sufficient to permit the partition 11 to be pressed down onto the bottom 6 by bearing on the handle 15 as seen in Figs. 1 and 2, and of 65 course by drawing upward on the handle the partition may be raised within the body or drawn out of the container entirely. The side bars of the loop pass through the notches 5 in the disk or cap 4. Projections 70 16 are formed on said side bars at points which stand below the cap when the latter rests on the shoulder 3 and the partition 11 rests on the bottom 6, and therefore, when the handle is grasped 75 and raised, these projections lift the cap automatically out of the mouth of the jar or container and open the same, and the cap or disk is drawn upward with the loop.

A third element is what I will call the 80 "clamp" the same being made of wire and preferably of aluminum wire. This wire is bent at its center into a semi-circular loop which is of a size to fit closely around the body 1 just beneath the shoulder 2, from 85 each end of the loop the wire passes outward, as at 21, is then bent and carried upward as at 22 where it passes alongside the thickened portion of the container, is then bent and carried inward as at 23, and is finally 90 formed into an eye 24 which embraces one side of the loop 14 above the projection 16.

When now the parts are in place as seen in Figs. 1 and 2, the bend or loop 20 of the clamp is snapped under the shoulder 2 and 95 the eyes 24 thereof frictionally engage the sides of the loop 14 so that the latter is held in the position illustrated and the partition 11 rests on the bottom. If we assume that the container is full of milk, cream soon rises 100 thereon and can be distinguished by looking through the glass wall. When it becomes desirable to pour off the cream and retain the milk, the operator moves the clamp to disengage the loop 20 from beneath the 105 shoulder and swing it aside. This relieves the binding action of the eyes 24 on the side stretches of the loop 14, and thereafter the latter may be moved upward by drawing on its handle, so that the partition 11 is 110 raised to the point indicated in dotted lines in Fig. 2, the cap or disk 4 being meanwhile

drawn out of the mouth, as suggested above. The operator now puts his fingers across the upper end of the container and astride the loop 14, and by tilting the device the 5 cream above the partition is readily poured off and very little milk will escape, being only such as runs through one of the notches 5. The partition may now be drawn entirely out of the container and the milk poured 10 out or the partition may be restored to its original position and the milk poured off. The parts can be entirely disconnected for cleansing at any time, and, as above suggested, the device may be used for separating 15 other things than milk and cream. I do not wish to limit myself to the materials, suggested, but give them only as my preference.

The foregoing description and the drawings have reference to what may be considered the preferred, or approved form of my 20 invention. It is to be understood that I may make such changes in construction and arrangement and combination of parts, materials, dimensions, et cetera, as may prove 25 expedient and fall within the scope of the appended claims.

Having thus fully described my invention, what I claim as new and desire to secure by Letters Patent is:—

30 1. The combination with a cylindrical container having an open mouth, and a disk-like closure therefor having oppositely disposed notches; of a partition movably mounted within said container, a loop whose 35 lower end loosely engages said partition and whose side stretches pass upward through the notches in said closure, and projections on said stretches for the purpose set forth.

2. The combination with a container having 40 an upwardly facing shoulder around its open mouth, and a disk-like closure resting on said shoulder and having two openings; of a partition movably mounted within said container, a loop whose lower end is pivotally connected with said partition and whose side stretches pass upward through the openings in said closure, and projections on said stretches standing beneath the closure when the partition rests on the bottom of the container.

50 3. The combination with a jar thickened around its mouth and provided with an upwardly facing shoulder, a disk-like closure resting on the latter and having notches near its edges, a partition movably mounted within said jar, and a loop connected at its lower end with said partition and having stretches rising within the body and passing through said notches and connected at their upper ends, the stretches having elements thereon beneath the closure when the partition rests on the bottom; of a clamp detachably engaging the neck of the jar and having its ends upturned and engaging said stretches, 60 for the purpose set forth.

4. In a compartment container, the combination with a body cylindrical on its interior and having an open mouth, and a removable closure of such mouth; of a partition adjustable vertically within said body, 70 a rod whose lower end is connected with said partition and whose body leads upward out of the mouth, the closure having an opening for its passage, and means for holding the rod and partition in adjusted positions. 75

5. The combination with a cylindrical container having a shoulder around its open mouth, and a disk-like closure resting on said shoulder and having oppositely disposed notches; of a partition movably 80 mounted within said container and having perforated lugs, a loop whose lower end loosely engages said lug and whose side stretches pass upward through the notches in said closure, and projections thereon for 85 the purpose set forth.

6. The combination with a container having an upwardly facing shoulder around its open mouth; and a disk-like closure resting on said shoulder and having oppositely disposed notches; of a partition movably 90 mounted within said container, a loop whose lower end is pivotally connected with said partition and whose side stretches pass upward through the notches in said closure, 95 and projections on said stretches standing beneath the closure when the partition rests on the bottom of the container, and a handle at the upper end of said stretches.

7. The combination with a jar thickened 100 around its mouth and provided with a downwardly facing shoulder and an upwardly facing shoulder; a disk-like closure resting on the latter and having notches near its edges, a partition movably mounted within said jar, and a loop connected at its lower end with said partition and having stretches rising within the body and passing through said notches and connected at their upper ends, the stretches having elements thereon 110 beneath the closure when the partition rests on the bottom; of a clamp detachably engaging beneath said downwardly facing shoulder and having its ends upturned and engaging said stretches, for the purpose set forth. 115

8. The combination with a container having a downwardly facing shoulder around its open upper end, a partition movably disposed within said container, and a loop connected at its lower end with said partition and having side stretches rising out of said mouth; of a clamp whose center is sprung around the container beneath said shoulder, each end thereof being carried out, thence upward, then inward over the upper end of the container, and into contact with one of said stretches, for the purpose set forth. 120 125

9. The combination with a container having a downwardly facing shoulder around its open upper end, a partition movably dis- 130

posed within said container, and a loop connected at its lower end with said partition and having side stretches rising out of said mouth; of a clamp whose center is sprung 5 around the container beneath said shoulder, each end thereof being carried outward, thence upward, thence inward over the upper end of the container and formed into an eye engaging one of said stretches, for the

10 purpose set forth.

10. The combination with a container having a downwardly facing shoulder around its open upper end, a partition mov-
ably disposed within said container, and a
15 loop connected at its lower end with said partition and having side stretches rising out

of said end; of a clamp of spring wire comprising a semi-circular center adapted to spring around the body of the container beneath the shoulder, the ends thereof being 20 carried outward beneath said shoulder, thence upward, and finally inward over the upper end of the container and formed into loops for clamping the said stretches, as de-
scribed.

25

In testimony whereof I affix my signature in presence of two witnesses.

MATILDA HAMEL.
